UNITED STATES PATENT OFFICE.

JOSIAH ALLISON HOGUE, OF ARCADIA, FLORIDA.

DESIGN FOR A HANGER FOR QUILTING-FRAMES.

SPECIFICATION forming part of Design No. 31,976, dated December 12, 1899.

Application filed November 14, 1899. Serial No. 736,996. Term of patent 7 years.

To all whom it may concern:

Be it known that I, JOSIAH ALLISON HOGUE, a citizen of the United States, residing at Arcadia, in the county of De Soto, State of Florida, have invented and produced a certain new and original Design for a Hanger for Quilter-Frames, of which the following is a specification, reference being had therein to the accompanying drawings, in which—

- 10 o Figure 1 is a perspective of the hanger; Fig. 2, a side elevation thereof, and Fig. 3 an end view.

As shown in the drawings, the leading or material feature of my design consists of the 15 straight hanger A, having at its lower end diverging members B, which terminate in

curved sockets C at each side of the hanger A. Between these sockets a straight brace D extends, and the upper end of the hanger is formed with a loop E, having a depending 20 straight end E'.

Having described my invention, what I claim as new, and desire to secure by Letters Patent, is—

The design for a hanger for quilting-frames 25 as herein shown and described.

In testimony whereof I affix my signature in presence of two witnesses.

JOSIAH ALLISON HOGUE.
